BUTTON OR SIMILAR ARTICLE

Lester Sloane, Brookline, Mass.

Application May 7, 1948, Serial No. 146,225

Term of patent 3½ years

(Cl. D17—2)

To all whom it may concern:

Be it known that I, Lester Sloane, a citizen of the United States, residing in Brookline, in the county of Norfolk and State of Massachusetts, have invented a new, original, and ornamental Design for a Button or Similar Article, of which the following is a specification, reference being had to the accompanying drawing, forming a part thereof, in which Figure 1 is a front view of the button or similar article showing my new design, and Figure 2 is a side view thereof.

The essential features of my design for a button are shown in full lines.

I claim:

The ornamental design for a button or similar article, as shown and described.

LESTER SLOANE.
